UNITED STATES PATENT OFFICE.

STEPHEN OLOP, OF WASHINGTON, DISTRICT OF COLUMBIA, ASSIGNOR OF ONE-HALF TO
GAINS M. BRUMBAUGH, OF WASHINGTON, DISTRICT OF COLUMBIA.

SAFETY-PIN.

No. 908,693.

Specification of Letters Patent.

Patented Jan. 5, 1909.

Application filed February 10, 1908. Serial No. 415,181.

To all whom it may concern:

Be it known that I, STEPHEN OLOP, a citizen of the United States, residing at Washington, District of Columbia, have invented 5 certain new and useful Improvements in Safety-Pins; and I do hereby declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 This invention relates to new and useful improvements in fastening means for safety pins and the object of the invention is to produce a simple and efficient device of this nature consisting of two sliding guards, each 20 provided with a slot which, when brought into registration, will allow a pin to be inserted therethrough after which the resiliency of the arms of the pin will cause the slots to be thrown out of registration, there- 25 by securely fastening the pin between the guards.

The invention comprises various other details of construction and combinations and arrangements of parts which will be herein- 30 after fully described and then specifically defined in the appended claims.

The invention is illustrated in the accompanying drawings, in which:—

Figure 1 is a perspective view of my 35 safety pin. Fig. 2 is a view showing the pin receiving slots out of registration. Fig. 3 is a detailed view of a modified form. Fig. 4 is an end view of the modified form shown in Fig. 3. Fig. 5 is a detail of the form 40 shown in Fig. 3. Fig. 6 is a modified form, and Fig. 7 is an end view of the form shown in Fig. 4 with the plate inclosing one end removed.

Reference now being had to the details 45 of the drawings by letter, A and B designate two guard plates, the former of which is fastened to one end D' of the wire D' while the other guard plate is fastened to the end D² of a second wire D³, each of said ends being 50 preferably curved or bent as shown in dotted lines in the drawings. Each plate is adapted to clamp an end of the wire and is securely held thereon. Each guard plate is preferably formed by bending the plate upon

itself, a space intervening between the walls 55 of one plate A, while the other plate when folded is adapted to slide between the walls of the other. Said plate A is provided with slots A' formed in the opposite walls thereof and the plate B is provided with a similar 60 slot B'.

F designates a plate which is fastened to the angled portions N of the wires.

K designates a pin, reinforced and held by the plate F which frictionally clamps the 65 same. The pin K forms a part of the wire D' which is normally parallel with the wires forming the sides of the frame. The bent portions of the two wires D' and D³, which are engaged by the plate or casing F, se- 70 curely hold the wires in the positions shown in the drawings. Said pin and also the por- 75 tions of the wires D' and D³, forming the sides of the frame are resilient whereby, when it is desired to allow the pin to be fas- 80 tened between the guards, the ends of the wires D' and D³ may be pressed together sufficiently to bring the slots in registration to allow the pin to pass therethrough and, after pressure is relieved from the wires, the 85 latter will spring out into the position shown in Fig. 2 of the drawings which will hold the slots from registration.

In Figs. 3, 4 and 5, it will be noted that the modifications show the wire bent to form a 85 coil K² which projects at an angle to the pin and, in Fig. 4, the metallic casing covering one end of the device has a lateral projection K³ to incase the coil K².

In Fig. 6 is shown a slight modification in 90 which the pin is made of two wires D⁶ and D⁷, the former of which has the pin D⁸ and has a portion D⁹ bent at right angles to the side and bent to form an inverted loop D¹⁰, while the other wire is bent at a right angle at D¹¹ 95 and also has an inverted loop D¹² and is further extended to form a loop D¹³ forming a guard to the pin D⁸.

In Figs. 1 and 2, the front part of the plates A and B constitute members having 100 pin openings A' and B' transversely there- through while the remainder of said plates constitutes means coacting with said mem- bers to inclose the free end of said pin for retaining the latter after the resilient wires 105 have returned to their normal positions. In Fig. 6, the parts D⁶ and D⁷ constitute such members with the pin openings formed by

the loops D¹⁰ and D¹², while the back of the loop D¹³ constitutes the means coacting with said members as just described.

From the foregoing, it will be noted that, by the provision of a pin made as shown and described, a simple and efficient device is afforded whereby the point of the pin may be held from becoming detached from the guard.

10. What I claim to be new is:—

1. A fastening device for pins comprising two resilient wires, the corresponding ends of which are bent laterally toward each other and each end being provided with a member having a pin opening transversely therethrough, said pin openings being adapted to be brought into registration with each other when the resilient wires are compressed, a pin fixed at one end intermediate said resilient wires and adapted to enter said openings when in registration, and means coacting with said members to inclose the free end of said pin for retaining the latter after the resilient wires have returned to their normal positions and so arranged that the pin may be moved laterally when in a locked relation and independent of said wires, as set forth.

2. A fastening device for pins comprising a wire having two resilient ends, a guard plate fixed to each end, each guard plate having a

slot, the two slots being normally out of registration, a pin fastened to said wire and adapted to be inserted through the slots when in registration, as set forth.

3. A fastening device for pins comprising a wire which is bent forming two resilient ends, a guard plate fixed to each end, each guard plate having a slot in the edge thereof, one guard plate adapted to telescope within the other, a fixed pin intermediate the resilient ends of said wire and adapted to be inserted through the slots when in registration and held by the walls of said guard plate, as set forth.

4. A fastening device for pins comprising a wire which is bent to form two resilient ends, a pin point, a plate holding the same to the bent portion of said wire and intermediate the resilient ends, a slotted guard plate fixed to each end of the wire, one of said guard plates adapted to telescope within the other and designed to receive the pin point, as set forth.

In testimony whereof I hereunto affix my signature in the presence of two witnesses.
